UNITED STATES PATENT OFFICE.

FRIEND W. SMITH, OF BRIDGEPORT, CONNECTICUT.

DESIGN FOR LEAVES OF BUTT-HINGES.

SPECIFICATION forming part of Design No. 16,065, dated April 28, 1885.

Application filed January 14, 1885. Term of patent 7 years.

To all whom it may concern:

Be it known that I, FRIEND W. SMITH, a citizen of the United States, residing at Bridgeport, in the county of Fairfield and State of Connecticut, have invented a certain new and original Design for the Leaves of Butt-Hinges; and I do hereby declare the following to be a full, clear, and exact description of the invention, such as will enable others skilled in the art to which it appertains to make and use the same.

Reference is to be had to the accompanying drawing, forming a part hereof, which shows an elevation of my newly-designed hinge.

Heretofore hinges of this description have been made in which the exposed face of the leaves presented, when viewed in elevation, a scalloped or figured outline, or else said face has been perfectly plain.

The leading feature of my design consists in two or more parallel shallow channels or grooves extending across the exposed face of the leaf of the hinge.

A is the leaf of the hinge, and B the channels or grooves.

Having described my invention, what I claim is—

The design for the leaves of a butt-hinge, the same consisting in a hinge provided with a plain leaf having a single series of parallel grooves extending the length of the leaf, substantially as shown.

In testimony whereof I affix my signature in presence of two witnesses.

FRIEND W. SMITH.
